UNITED STATES PATENT OFFICE

155,335

DESIGN FOR AN AIRPLANE

Howard C. Delcher, Jr., and Carl Lawrence Brockman, Baltimore, Md., assignors to The Glenn L. Martin Company, Baltimore, Md.

Application October 28, 1947, Serial No. 142,174

Term of patent 14 years

(Cl. D71—1)

To all whom it may concern:

Be it known that we, Howard C. Delcher, Jr., and Carl Lawrence Brockman, citizens of the United States and residents of city of Baltimore, State of Maryland, have invented a new, original, and ornamental Design for an Airplane, of which the following is a specification, reference being had to the accompanying drawings, forming a part thereof.

Figure 1 is a fragmentary, perspective view of the fuselage of an airplane, broken away to show the lavatory in the interior thereof.

Figure 2 is a fragmentary, sectional plan view of the corresponding portion thereof.

Figure 3 is a fragmentary, vertical sectional view of the corresponding portion.

Figure 4 is a plan view of the complete airplane.

The characteristic features of our design reside in those portions, especially of the interior, shown by means of full lines in the drawing.

We claim:

The ornamental design for an airplane, substantially as shown and described.

HOWARD C. DELCHER, JR.
CARL LAWRENCE BROCKMAN.
